UNITED STATES PATENT OFFICE.

JOHN BARBORA, OF BUFFALO, NEW YORK.

BEDSTEAD ATTACHMENT.

1,133,696.

Specification of Letters Patent. Patented Mar. 30, 1915.

Application filed June 22, 1914. Serial No. 846,645.

To all whom it may concern:

Be it known that I, JOHN BARBORA, a subject of the Emperor of Austria-Hungary, residing at Buffalo, in the county of Erie 5 and State of New York, have invented certain new and useful Improvements in Bedstead Attachments, of which the following is a specification.

This invention relates to certain new and 10 useful improvements in bedstead attachments.

An object of the present invention is to provide an attachment for bedsteads in the 15 form of a bracket support carrying a table top or a receptacle structure to be used especially in a sick-room.

A further object of the invention is to provide a table or receptacle attachment for bedsteads that may be easily and quickly 20 adjusted as to height and be retained in its adjusted position, while the same may be moved in an angular direction and held in such position.

With the above general objects in view 25 and others that will appear as the nature of the invention is better understood, the same consists in the novel construction, combination and arrangement of parts to be hereinafter more fully described and then 30 claimed.

In the accompanying drawings which 35 show the preferred embodiment and modification of the present invention, and to which reference is had herein by like characters designating corresponding parts throughout the several views:—Figure 1 is a front elevational view of the device attached to the side rail of a bed. Fig. 2 is a side elevational view of the same. Fig. 40 3 is a view taken on line III—III of Fig. 1. Fig. 4 is a vertical side elevational view partly in section of a modified form of the invention. Fig. 5 is a front elevational view of the same partly broken away, and, Fig. 45 6 is a detail plan view of the spider for holding the table top in its laterally-adjusted position.

Briefly described, the invention embodies in its preferred form, an upright support 50 adapted to be detachably secured to the side rail of a bed and carrying a rack bar to be engaged by locking pawls carried by a cross-arm which is mounted on the vertically-adjustable arm carrying a table top or receptacle. In the modified form of the 55 invention, the support carries at its upper

end a threaded member adapted to receive bracket arms that support the table top, the bracket arms being adjustable vertically and laterally, with means for holding the 60 same in its adjusted position.

Referring more in detail to the accompanying drawings, and particularly to the preferred form of invention as shown in Figs. 1, 2, and 3, the reference numeral 10 designates the side rail of a bed, which as shown is of angle-iron construction, although the present invention is applicable to a bed of wooden construction. The main support of the attachment consists of an 15 upright member 11 having projecting from one face thereof an upper lug 12 and lower lug or projection 13. The lower lug 13 carries the lateral projections 14 apertured to provide a guide for the depending arms 15 carried by the clamping block 16. A screw 17 passes through the lower lug 13 and has an operating wheel 18 upon the lower end thereof, and has a loose connection as at 19 with the clamping block 16. Projecting 20 from the opposite side of the vertical support is a pair of spaced lugs 20 apertured for the reception of a vertical arm 21. The arm 21 has a head block 22 suitably-fastened to the upper end thereof, which block carries 25 a plurality of preferably curved supporting arms 23 having mounted upon the upper ends thereof the box receptacle 24. The box receptacle 24 as shown in Fig. 1, is preferably provided with a drawer slide 25 and 30 has secured to one side thereof a spring arm 26 which may act as a clamp for the securing of papers, napkins, or any articles to be placed therebetween. The spaced lugs 20 have connected thereto upon opposite sides 35 thereof the rack bars 27, the teeth of which are disposed outwardly thereof and coöperate with means carried by the arm to hold the receptacle or table top in an adjusted 40 position. This means consists in securing to 45 the arm 21 in any suitable manner, such as indicated at 28, a cross-arm 29 having the outer ends thereof bifurcated as at 30 and adapted to receive in said bifurcated ends, the rack bars 27, as clearly illustrated in 50 Fig. 3. Each of the bifurcated ends carries a bale 31 having freely pivoted thereto a pawl 32, the pawl in its operative position engaging the teeth of the rack bar 27 and holding the table top or receptacle 24 in an 55 adjusted position. The particular location 60 of the lugs 20 operating in connection with

the arm 21 will position the receptacle 24 over a bed, the height of the receptacle being controlled by the pawls 32 engaging the rack bar 27, such pawls being carried by the cross-arm which is supported on the vertical arm 21.

A modified form of the invention is shown in Figs. 4, 5, and 6, and consists of the supporting member comprising the upright 10 11, the upper and lower projections 12 and 13 and the clamping block 16 operating in connection with the screw 17 and hand wheel 18 in a manner similar to the form shown in Figs. 1 to 3. The upper lug 20 of 15 the form shown in Fig. 4 has secured therein by the pin 33, a vertically-disposed threaded rod 34 provided with an eye 35 at its upper end and having connected thereto by the chain 36 a locking pin 37. A pair 20 of nuts 38 are provided on the rod 34 and suitably spaced as shown in Fig. 4, the lower nut constituting a seat for the lower arm 39 of a bracket 40, while the upper end tends to limit the upward movement of the 25 upper arm 41 of said bracket 40. A table 42 of suitable shape and construction is carried by the bracket 40. The locking pin 37 passes through an opening 42' provided in the upper bracket arm 41 and passes 30 through selected openings 43 provided in the spider 44 secured as at 45 to the threaded rod 34. The height of the table 42 may be easily adjusted by moving the nuts 38 over the threaded rod 34 while the lateral 35 position of the table may be controlled by the pin 37 passing through the selected opening 43 in the spider 44.

The present invention is particularly adapted for sick rooms where the patient is 40 confined in a bed, and is of such construction that the same may be easily and quickly attached to the side rail of either a wooden or iron bed with the upper receptacle or

table top adjusted over the bed as to height and lateral disposition.

45

While the drawings show the preferred embodiments of the present invention, I do not wish to be confined to the exact details of construction shown, as various forms, modifications and arrangement of the parts 50 as shown may be had without departing from the spirit and scope of the invention as claimed.

What I claim as new is:—

1. In a device of the class described, an 55 upright support comprising complementary clamping members operating in connection with the side rail of a bed, spaced lugs carried by the opposite side of the support, rack bars connecting the side lugs, a vertical arm movably mounted in the lugs, a cross arm carried by the vertical arm and having each end thereof bifurcated to provide a pair of arms to inclose the rack bars, and pawls pivoted to the cross-arms and arranged to engage the rack bars.

2. In a device of the class described, an upright support comprising complementary clamping members operating in connection with the side rail of a bed, spaced lugs carried by the opposite side of the support, rack bars connecting the spaced lugs and having their teeth disposed outwardly, a vertical arm movably mounted in said lugs, a cross-arm carried by said vertical arm and 75 having each end thereof bifurcated to provide a pair of arms inclosing the rack bars, and pawls pivoted in the ends of the cross-arms and adapted to engage the rack bars.

In testimony whereof I affix my signature 80 in presence of two witnesses.

JOHN BARBORA.
